ROTARY LAWN SPRINKLER

John D. Beamer, West Covina, Calif., assignor to Rain
Bird Sprinkler Mfg. Corp., Glendora, Calif.

Filed Feb. 10, 1975, Ser. No. 548,412

Term of patent 14 years

Int. Cl. D23—01

U.S. Cl. D23—7

FIG. 1 is a rear perspective view of a rotary lawn sprinkler embodying my new design;

FIG. 2 is a top plan view thereof;

FIG. 3 is a side elevational view thereof as seen from the opposite side of FIG. 1;

FIG. 4 is a front elevational view thereof; and

FIG. 5 is a bottom plan view thereof.

I claim:

The ornamental design for a rotary lawn sprinkler, substantially as shown.
